UNITED STATES PATENT OFFICE

GEORGE ADELBERT ACER, OF MIDDLEPORT, NEW YORK

ATTACHING HOOK FOR BASKET COVERS

Application filed July 21, 1926. Serial No. 123,958.

This invention relates to a fastening hook for use in connection with slatted covers of bushel baskets and the like.

Heretofore when it has been desired to partly or entirely remove the covers for the purpose of inspecting the contents or for repacking, considerable difficulty has been experienced in unfastening the covers and as a general rule some kind of tool has been

10 necessary.

It is an object of the present invention to provide an attaching hook which can be applied readily without the use of a special tool and can also be readily disconnected to 15 allow the cover to be partly or entirely removed.

20 A further object is to provide a fastening device of this character which will remain in proper position during ordinary handling and prevent the cover from becoming detached.

25 A further object is to provide a fastening hook which also provides a rest for the cover so as to hold it spaced from the basket at the margin.

With the foregoing and other objects in view which will appear as the description proceeds, the invention resides in the combination and arrangement of parts and in the 30 details of construction hereinafter described and claimed, it being understood that changes in the precise embodiment of the invention herein disclosed may be made within the scope of what is claimed without departing 35 from the spirit of the invention.

In the accompanying drawings the preferred form of the invention has been shown.

In said drawings,

40 Figure 1 is a plan view of a bushel basket having the present improvements combined therewith.

Figure 2 is a side elevation of a portion thereof.

45 Figure 3 is a detail view of one of the fastening hooks.

Referring to the figures by characters of reference A designates a basket provided at its top with a hoop B. This basket has the usual slatted cover C and, as shown in Figures 1 and 2, one of the slats D has its ends

projecting beyond the periphery of the cover so as to be fitted within the wire handles E of the basket. Other slats, indicated at F, are extended across and form part of the cover, these slats F being preferably at right angles to the slats D.

The hook constituting the present invention has been shown in detail in Figure 3 and includes a single length of stiff wire bent to provide a straight intermediate portion 1 the ends of which merge into arms 2 having hooked terminals 3. Intermediate portions of these arms are offset to provide rests or shoulders 4.

In practice the fasteners are placed astride the slats F and are positioned at diametrically opposed portions of the cover as shown in Figure 1. The upper portions of the arms are extended along the inner sides of the margin of the cover while the rests or shoulders 4 extend under the margin of the cover. Thus the lower portions of the arms can be positioned outside of the hoop B. As the cover is supported by the contents of the basket, it will be apparent that by pressing 75 downwardly on the cover the same can be sprung so as to permit the hooks 3 to engage the lower edge of the hoop B. Thus the cover will be held properly assembled with the basket and the shoulders or rests 4 will support the marginal portion of the cover normally away from the top of the basket as shown in Figure 2. Whenever it is desired to examine the contents of the basket it merely becomes necessary to press upon that 80 portion of the cover engaged by the fastener. Thus the thrust will be transmitted through the shoulders or rests 4 to the arms 2 and will result in the withdrawal of the hooks 85 3 from the hoop B.

The constant pressure of the contents of the basket against the cover will be sufficient to hold the hooks in engaging position under normal conditions. Thus it will be seen that 90 the contents of the basket can be readily examined whenever desired or can be repacked without requiring the use of any special tools for the purpose of disconnecting the cover from the basket.

What is claimed is:

The combination with a basket having a hoop and a cover therefor, of a fastener formed in a single length of wire bent to provide a straight intermediate portion merging into arms, said fastener straddling a portion of the cover inwardly from the margin thereof, each of said arms being outwardly offset between its ends to provide a shoulder 10 engaging the lower edge of the margin of the cover, the lower portions of the arms being extended outside of the hoop of the basket and bent to provide terminal hooks the distance between the shoulders and the hooks 15 being greater than the width of the hoop, the hooks being extended upwardly toward and under the respective shoulders for engaging between the hoop and the adjacent portion of the basket, said arms being shift- 20 able longitudinally under pressure on the basket cover to bring the shoulders against one edge of the hoop and to disengage the hooks from the other edge of the hoop.

In testimony that I claim the foregoing as 25 my own, I have hereto affixed my signature.

GEORGE ADELBERT ACER.
